AUTOMOBILE BODY

Milton H. Allen, Richmond Hill, N. Y.

Application July 10, 1950, Serial No. 11,061

Term of patent 14 years

(Cl. D14—3)

To all whom it may concern:

Be it known that I, Milton H. Allen, a citizen of the United States, residing at Richmond Hill, in the county of Queens and State of New York, have invented a new, original, and ornamental Design for an Automobile Body, of which the following is a specification, reference being had to the accompanying drawings, forming a part thereof:

In the drawings:

Figure 1 is a side elevational view of an automobile body showing my new design.

Figure 2 is a fragmentary front elevational view.

Figure 3 is a fragmentary top plan view of the portions shown by full lines in Fig. 1.

The characteristic features of my design, reside in the portions shown by means of full lines in the drawing.

I claim:

The ornamental design for an automobile body, as shown and described.

MILTON H. ALLEN.
